UNITED STATES PATENT OFFICE.

JOHN CHILD BARBER, OF ST. PAUL, MINNESOTA.

CAR-TRUCK.

SPECIFICATION forming part of Letters Patent No. 506,460, dated October 10, 1893.

Application filed May 13, 1893. Serial No. 474,083. (No model.)

To all whom it may concern:

Be it known that I, JOHN CHILD BARBER, a citizen of the United States, residing at St. Paul, in the county of Ramsey and State of Minnesota, have invented certain new and useful Improvements in Car-Trucks; and I do hereby declare the following to be a full, clear, and exact description of the invention, such as will enable others skilled in the art to which it appertains to make and use the same.

My invention relates to swing beam car-trucks, of the class shown and described, in my several prior United States patents, to-wit: Patents No. 370,758, of date October 4, 1887; No. 383,688, of date May 29, 1888; and No. 433,063, of date July 29, 1890.

In its general design, so far as the construction for permitting the lateral motion to the truck-bolster or beam is concerned, the truck, which I have herein shown and described, is similar to the truck shown and described in the last two of the above identified patents.

My present invention is directed to certain details of the construction, with a view of rendering the same more efficient, and with a view of adapting the same to the use of elliptic springs, for easy riding cars, stock and other special classes of freight cars.

To these ends, my invention consists of certain novel devices and combinations of devices, which will be hereinafter fully described and defined in the claims.

The accompanying drawings illustrate my improved truck, wherein, like letters referring to like parts, Figure 1 is a plan view, and Fig. 2 a side elevation of the truck. Fig. 3 is a cross section of the same, on the irregular line X' X' of Fig. 1, some parts being broken away. Fig. 4 is a sectional view on the line Y' Y' of Fig. 3, looking outward, some of the parts being removed, and others broken away. Fig. 5 is a sectional view, on the same line, as Fig. 4, looking inward, with all the parts in position, parts of the side frame being broken away. Fig. 6 is a section on the line Z' Z' of Fig. 3, with some parts broken away, and all the parts above the combined spring-caps and roller bearings removed. Fig. 7 is a cross section of the truck beam or bolster, on the line Z' Z' of Fig. 1. Fig. 8 is a similar view on the same line, after the chafing irons have been secured in place. Fig. 9 is a detail in

end view, of one of the wooden sections of the bolster; and Fig. 10 is a plan view of the same turned down sidewise. Fig. 11 is a detail, showing one of the spring seat hangers, in end elevation. Figs. 12 and 13 are details, showing spring-seat in plan and end view respectively.

On the journals of the truck-axle *a*, are located the journal boxes *a'*, held in place by journal-bolts *a*² passing through seats in the boxes and securing the same to the pedestal tie-bars *b* and the arch-bars *b'* *b*², which together constitute the trussed side frames of the truck.

d are the bolster columns with outer end and bolt-seat flanges *d'* and *d*², respectively, spaced apart from each other between the arch-bars *b'* *b*², and rigidly secured to the said arch-bars and pedestal tie-bars *b*, by column-bolts *d*³. These bolster columns are located at equi-distant points on the opposite sides of the longitudinal centers of the side frames.

e are the transoms riveted to the bolster columns, composed of channel-iron, with their ends abutting against the outer end flanges *d'* of the bolster columns, and their upper and lower outturned flanges fitting between the upper and intermediate bolt-seat flanges *d*² of the bolster columns. By this construction, the bolster columns and the transoms, and the side frames of the truck, are rigidly secured together, and the weight or strain on the transoms, will not be taken entirely by the rivets, but will be taken largely by the bolt seat flanges *d*² and the end flanges *d'* of the bolster columns. In other words, when the transoms are in position, and the column-bolts *d*³ have been passed through the flanges of the transoms, and the bolt-seat flanges of the columns and secured to the bars of the side-frames, the transoms and bolster-columns will be interlocked, without regard to the rivets, which simply render the connections more rigid and secure.

e' are spring-seat hangers riveted to the transoms, inward of the side frames, and spaced apart short distances from the bolster-columns. *f f' f*² are spring-seats supported by the said hangers *e'* and the lower arch bars *b*² of the side frames. The shouldered surfaces *f'* of the spring-seats engage the vertical opposing faces of said hangers.

and lower arch-bars; and the upturned flanges f^2 engage between the bolster columns; by which means, the spring-seats are prevented from either lateral or transverse movement.

5 The said spring-seats rest loosely on their supports, and are removable at will, when the springs are not in position. The elliptic springs f^3 rest on the seats f' , and between the bolster columns d , arranged lengthwise of

10 the bolster or transversely to the side-frames.

f^4 are spring-caps, having on their faces transverse roller-seats f^5 of curvilinear form in cross section. These spring-caps f^4 rest loosely on the tops of the springs, and are

15 provided with end projections or guide-lugs f^6 , which work between the inner vertical faces of the bolster columns d , and the outer vertical faces of the spring-seat hangers e' , as guides; by which means, the spring-caps

20 and springs are held in their proper working position. The caps f^4 have down flanges f^7 co-operating with the up flanges f^2 on the spring seats f' , for holding the springs f^4 . Roller bearings g work on the seats f^5 of the

25 spring-caps f^4 , and support the laterally movable swing-beam or truck-bolster. The body of the truck-bolster is composed of parallel longitudinally arranged wooden and metallic sections k k' , which are rigidly secured together, by cross-bolts or rivets k^2 . The bolster carries near its outer ends, on its under surface, roller-caps or bearing-plates k^3 , having transverse seats k^4 of curvilinear form in cross section, for co-operation with the roller

30 bearings g , and the seats f^5 of the spring-caps f^4 .

The bolster body is reinforced by a pair of truss-rods k^5 , working over a truss-bridge k^6 secured to the under surface of the bolster, with bearing posts on the opposite sides of the longitudinal center of the bolster. The truss-rods pass diagonally through the end portions of the bolster body, at points inward of the outer margins of the bolster and equidistant from the transverse center of the same; and have screw-threaded ends engaged by draw-nuts k^7 , working against truss-rod washer-castings or bolster-end caps k^8 . This construction distributes the strain equally, on the end surfaces of the bolster, and prevents the buckling strain from the truss-rods and bridge from being taken on a single line, at the center of the bolster. In other words, having regard to the buckling strain, the double post k^6 distributes the buckling strain from the truss-rods over a wide surface, at the central part of the bolster body. It may be further noted, in respect to the construction of the bolster, that the holes or seats k^9 , for

40 the truss-rods k^5 , are open grooves, formed on the inner faces of the outside wooden sections k of the bolster body, which is a convenience for putting the parts together.

The bolster body carries, on its top surface, the usual center plate k^{11} , and the side bearing and lateral motion stop castings k^{12} . The vertical flanges of the castings k^{12} come in

contact with the top members b' of the arch-bars, to limit the lateral or swinging motion of the bolster on the bearing rollers g .

70 The castings k^{12} are provided with side bearing rollers k^{13} , for the car-body bolster, which are of slightly conical form, curved concentrically with the center of the truck.

The bolster body is provided with chafing irons n n' , the two parts of which are formed at an acute angle to each other. These chafing irons are of spring-metal, and the angular relation of their parts permits the same to be drawn down and secured in position by a single lag-screw n^2 , applied to the horizontal part n' of the chafing iron, as shown in Figs. 7 and 8. When the chafing irons are thus drawn into position, by the lag-screws, the vertical or chafing portions n of the said irons, 85 will hug the vertical outer surface of the bolster and be held in position, under the spring action of the parts. This construction gives cheaply made and easily applied chafing irons.

The chafing irons are located near the ends 90 of the bolster body, in position to bear against the inner faces of the bolster columns d . There is a great advantage in thus locating the chafing irons on the bolster; in that, by this arrangement, all the forward and backward thrusting strains or shocks from the bolster will be taken on the bolster columns and the side frames of the trucks. Under the application of the brakes, or from the sudden shocks given in switching cars, and in various other ways, the forward and backward strains or thrusts from the bolster, are very great.

Hitherto, so far as I am aware, the so-called friction or chafing plates, used on bolsters of this class, have been located in such position on the bolster, that the forward and backward thrusting strains from the bolster, would be taken on the transoms. The result, as proven by usage, has been that the transoms 105 are torn loose and the truck-frame sometimes broken down. By locating the friction plates or chafing irons, as I do, the entire strain is taken on the bolster columns, thereby falling directly on the side frames. Hence, the 115 transoms are entirely relieved from the thrusting strains on the bolster. The life of the truck is thereby greatly lengthened.

Having regard to the bearing rollers g and their seats on the spring-caps f^4 and in the 120 roller-caps k^3 , it will of course be understood, that these parts might be constructed for a greater or less number of roller bearings. A single roller, for example, could be used; but two or more are preferable for the better distribution of the strain.

Having regard to the bolster body, it is obvious that the relation of the wooden and metallic sections might be changed. For example, the bolster body might be composed 130 of four metallic and three wooden sections, arranged in alternate order with two of the metallic sections external and two of the same equidistant from the transverse center

of the bolster. In this event, the outside metallic sections, could be enlarged at the ends of the bolster, which enlargements would answer, for the frictional plates or chafing surfaces. The construction I have shown, however, forms a strong and serviceable bolster, with all the parts well arranged for durability.

The car-truck constructed as herein described, is strong and durable; and is well adapted for the use of elliptic springs suitable for passenger cars, caboose cars, stock cars, and other special classes of freight cars.

What I claim, and desire to secure by Letters Patent of the United States, is as follows:

1. In a car truck, the combination with the side frames and transoms, of spring seat hangers rigidly secured to the transoms, spring seats, supported by said hangers and side frames, springs on said seats, spring caps on said springs having on their faces transverse roller seats curvilinear in cross section, roller bearings working in said bearing seats and a truck bolster, supported by said roller bearings with freedom for lateral motion, substantially as described.

2. In a car-truck, the combination with the side frames and transoms, of the spring-seat hangers, rigidly secured to the transoms, spring-seats supported by said hangers and side-frames, elliptic springs resting in said seats, spring-caps on said springs, having on their faces transverse roller seats curvilinear in cross section, roller-bearings working in said bearing-seats, and the truck-bolster supported by said roller-bearings, with freedom for lateral motion, substantially as described.

3. In a car-truck, the combination with the truss-bar side frames, as described, of the bolster columns secured between the arch-bars of said frames, the transoms secured to said bolster columns, the spring-seat hangers, rigidly secured to the transoms, the spring-seats, supported by said side frames and hangers, elliptic springs resting on said seats between the said bolster-columns, spring-caps on the said springs, having on their faces transverse roller-seats curvilinear in cross section, roller bearings working on said bearing seats, and the truck bolster working between the transoms and bolster columns, with its ends resting on said roller-bearings, substantially as and for the purposes set forth.

4. In a car-truck, the combination with the

trussed side-frames, of the bolster columns secured between the arch-bars of said frames, the transoms secured to said columns, the spring-seat hangers secured to the transoms, and the loose removable spring-seats supported by said side-frames and hangers and provided with shoulders or raised under-surfaces engaging the vertical faces of the lower arch-bars and hangers, and with raised end flanges engaging the bolster-columns, for holding the said seats from lateral and transverse movement, substantially as described.

5. In a car-truck, the combination with the truss-bar side-frames, of the bolster columns, secured between the arch-bars, the transoms secured to said columns, the spring-seat hangers secured to said transoms, the spring-seats supported by said hangers and the lower arch-bars of the side-frames, the elliptic springs on said seats, between the said columns, and the combined spring-caps and roller-bearing seats resting on the springs, and provided with projecting end-lugs, working between the inner vertical faces of the said bolster columns and the outer vertical faces of said spring hangers as guides, substantially as described.

6. The bolster-chafing-irons nn' , constructed of spring-metal, with their parts formed at acute angles to each other, for application to the bolster by a single screw, substantially as described.

7. In a car-truck, the combination with side frames, of lateral motion truck bolsters, having friction plates or chafing irons at their ends, and working against rigid parts of the side frame, for relieving the transoms and taking the forward and backward strains of the bolster, directly on the side frames, substantially as described.

8. The combination with the truss bar side frames, of the bolster columns between and rigidly secured to the arch-bars and the lateral motion truck bolster, working between said bolster columns and provided with friction plates or chafing irons located near its ends and bearing against the said bolster columns, under the thrusting strains, on the bolster, substantially as described.

In testimony whereof I affix my signature in presence of two witnesses.

JOHN CHILD BARBER.
